UNITED STATES PATENT OFFICE.

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN.

CANCELING, INDORSING, AND COUPON-CUTTING ATTACHMENT FOR ADDING-MACHINES.

1,262,097.

Specification of Letters Patent.

Patented Apr. 9, 1918.

Application filed February 13, 1913. Serial No. 748,208.

To all whom it may concern:

Be it known that I, FRANK C. RINSCHE, a citizen of the United States, residing at Detroit, Wayne county, in the State of Michigan, have invented a certain new and useful Canceling, Indorsing, and Coupon-Cutting Attachment for Adding-Machines, of which the following is a specification.

The object of my invention is to provide simple and efficient mechanism coöperating with an adding machine and preferably used as an attachment thereto, whereby such work as the indorsing or canceling of checks and the like, or the receipting of bills and the 10 detaching or cutting of a stub or coupon or the same may be accomplished as an incident of the operation of the machine that records the amounts of such checks, bills, or the like. To this end I provide printing mechanism and also cutting or severing mechanism for the work to be done that requires the latter operation, and make provision for the operation of the printing mechanism by one of the usual power members 15 of the adding machine. Another object of my invention is to make provision for the canceling or marking and cutting of different sizes of checks, bills, and the like which are run through the machine and also 20 to insure the accurate or straight running of the checks, bills, etc., through the machine. My invention also includes other novel and advantageous features of construction and mode of operation which will be apparent 25 from the description hereinafter given.

In the drawings Figure 1 is a plan view of a portion of a Burroughs adding machine and of my attachment applied thereto; Fig. 2 a side elevation thereof; Fig. 3 a detailed 30 section on the line 3—3 of Fig. 2; Fig. 4 a section on the line 4—4 of Fig. 2; Fig. 4^a is a detail cross section of a printing block; Fig. 5 a sectional elevation on the line 5—5 of Fig. 4; Fig. 6, a plane section on the line 6—6 of Fig. 5; Fig. 7, a detail section on the line 7—7 of Fig. 4; Fig. 8, a somewhat 45 similar view showing a different position of the numbers when the adding machine handle has been turned forward; Figs. 9 and 10, 50 detail views of the means for preventing un-

even feeding of the paper; and Fig. 11 is a vertical cross section taken substantially on the line 11—11 of Fig. 2.

For the sake of a clear and definite description of my invention, I have chosen to 55 show the same in connection with the well known Burroughs adding machine such as exemplified in Burroughs United States Letters Patents Nos. 504,963 and 505,078, dated September 12, 1893, although, as will be obvious, 60 my invention is applicable to adding machines of different make and type without any departure from the spirit and scope of my invention. Moreover, while the particular Burroughs machine herein illustrated 65 is of the hand-operated type, the same being operated by the handle 367, yet my invention is equally applicable to the power-driven type of machine.

Referring to the particular embodiment 70 of my invention as illustrated in the drawings, the attachment includes a main frame, printing and cutting mechanism mounted therein, a frame plate connecting the main frame with one side of the adding machine 75 (here the left side thereof, Fig. 1), and operating connections between the movable part of the adding machine, such as one of its power members.

The main frame of the attachment is in 80 the form of a yoke 1 which is the preferred form, as it provides at the outer side an opening with the result that papers of greater width than the frame may be operated upon by the attachment in the manner 85 hereinafter made apparent. The two limbs of this yoke are in substantially parallel horizontal planes and the base of the yoke which is here the inner end or side thereof, adjacent the adding machine, is secured to 90 a frame plate 2, which in turn is detachably and adjustably secured to the frame or casting 3, of the adding machine, indicated generally by the reference character A. As shown more particularly in Figs. 4 and 6, 95 the main frame or yoke is provided with a vertical flange 1^a which is secured to the angularly shaped frame plate 2 in suitable manner, as by means of the screws 4. This frame plate is of a triangular form, shown 100

in Figs. 1 and 2, with two of the arms or branches 2^a and 2^b, extending in a substantially horizontal direction and away from each other, and provided at their ends with 5 angular slots. This plate also has a third arm or branch 2^c extending in a substantially vertical direction. The outer ends of the branches 2^a and 2^b are provided with angular slots 2^d adapted to receive the shoulder 10 screws 5, screwed into the lugs 3^a projecting laterally from the lefthand side of the adding machine casing Fig. 1. The lower or vertical branch of the frame plate is inclined at its lower end at a certain angle 15 and is adapted to rest upon and be secured to a lug 3^b on the lower side of the adding machine casing which lug has a corresponding inclination, Fig. 2. This branch 2^c is secured to the lug 3^b by means of screws 6 20 passing through the lateral flange 2^e of said branch and entering the lug 3^b, Fig. 4. In order to provide for a substantially vertical adjustment of the frame plate, I employ an adjusting screw 7, screw-threaded into the 25 flange 2^e and abutting against the face of the lug 3^b. The angle or inclination of the lower end of this branch or arm 2^c is at right angles to the direction or angle of the slots 2^d, with the result that when the screw 30 7 is adjusted, the movement of the entire frame plate is accommodated. This plate is adjustable so as to establish the registering relationship between the gearing hereinafter described.

35 Within the frame 1 there are mounted to rotate two parallel shafts 8 and 9, the former of which is mounted in the upper portion or limb of the yoke and the latter of which is mounted in the lower portion or 40 limb of the yoke. These two shafts carry the printing and cutting mechanisms and also the platens and feed rolls hereinafter described. The shaft 8 is positively driven through the connections with the adding 45 machine and the shaft 9 is driven by a gear connection with the other shaft.

Describing the driving connections between the adding machine and the shaft 8 and referring more particularly to Figs. 2, 50 3, and 4 and 6 to 8, the power to drive the attachment is taken from the power member 510, mounted on the shaft 501 of the adding machine. As shown in detail in Fig. 3, this shaft has a reduced end, received by the elongated hub 10 of a sector 55 11, this hub bearing in the usual side frame 100 of the adding machine and extending through the case 3 of the machine. The inner end of this hub engages a plate 12 by 60 means of co-operating clutch teeth between these parts, this plate 12 being secured by riveting or otherwise to one side of the usual arm 510 of the adding machine and here utilized as the power member with the re-

sult that the oscillating movements of said 65 arm are communicated to the hub 10 and sector 11. A screw 13 passing longitudinally through the outer end of the hub engages the reduced end of the shaft 501 and holds the shoulder 10^a against the side 70 frame 100. The sector 11 is here shown as secured to the outer end of the hub 10 and is provided with a depending arm 11^a to whose lower end is connected one end of a spring 14 whose other end is connected to a 75 stud 15 on some fixed part of the machine. The sector 11 is formed at its upper end as a segmental gear, including the gear teeth 11^b which mesh with a shrouded pinion or gear 16, mounted to rotate freely upon the 80 stud 17 screwing into the inner end of the shaft 8, Fig. 4. This pinion has a ratchet and pawl connection with the gear 18, secured to the shaft 8, such ratchet and pawl connection consisting of a ratchet wheel or 85 disk 19 secured to one side of the pinion 16 and having a single tooth 19^a, with which cooperates the pawl 20 pivoted to one side of the gear 18. Normally the point of the pawl is against the tooth of the ratchet disk 90 and when the pinion is rotated by the action of the sector, this tooth is brought back into the same relation at the end of the forward stroke of such sector, whereupon the spring 14 against whose tension the sector moved 95 forwardly then exercises itself, with the result that the ratchet tooth engages and moves the pawl together with the gear 18 secured to the shaft 8, thereby imparting a complete rotation of said shaft 8 and all of 100 the hereinafter described mountings thereon. The gear 18 meshes with a corresponding gear 21 mounted on the inner end of the other main shaft 9 and such latter shaft is thereby moved in unison with the shaft 8. 105 In order to disable the operation of the shafts 8 and 9, in case it should be desired to use the adding machine only, I employ a simple device for rendering the ratchet and pawl inoperative. To this end the pawl 20 110 is held pressed to its normal or working position by means of a flat spring 20^a, bearing against one of its two flat faces which are at right angles to each other, as clearly shown in Fig. 8. This pawl is provided 115 with a handle 20^b projecting through the slot 21^a in the upper portion of the frame plate 2 for convenient manipulation by the operator. Full lines in Fig. 8 represent the operative position of the pawl and the 120 dotted lines its inoperative or disabled position. It will be evident that when the pawl is in such latter position the movements of the adding machine will not be 125 communicated to the attachment any farther than the pinion 19 and its ratchet wheel or disk and the attachment will thereby be rendered inoperative.

In order to prevent over-rotation of the shafts 8 and 9, means are employed to stop the movements of the gears 18 and 21 at their normal or home position, beyond which they might otherwise be carried by momentum. Referring to Figs. 7 and 8, said means, as herein shown, comprise an arm 22 pivoted at 23 to the frame plate 2 and having a notch 22^a adapted to engage a stud 24 projecting laterally from one side of the gear 21. When the arm 22 is in its elevated position shown in Fig. 7 the gear 21 is free to rotate but just as this gear completes its rotation, this arm 22 is lowered to a position to engage the stud 24, as shown in Fig. 8. Normally the stud is engaged by the notch and this engagement is maintained by a spring 25 until the sector 11 arrives at the limit of its forward oscillation, whereupon the stud 26 thereon engages the under angular edge of the arm 22 raising the latter for a sufficient period of time to enable the stud and gear to rotate. Thereupon the arm or pawl 22 drops down against a limit-pin 27 in readiness to engage the stud as it approaches the home position.

Referring to the mountings upon the upper shaft 8, the printing mechanism comprises type holders 28, adjustably and removably secured to the shaft 8 in suitable manner, as by means of the clamping bolt 29, Figs. 4 and 4^a. These type holders contain the type 30 which represent the particular marking or printing which is intended to be impressed or printed upon the paper passing through the attachment. The inking device, Figs. 5 and 6, comprises the ink roller 31, of suitable construction and material and mounted to turn freely against the face of the type in the periphery of the type holders. As shown, this ink roller is mounted on a rod 32 supported between the side arms 33 of a frame 34 which is formed as a unit construction with the type holder 28, with the result that such unit construction can be easily adjusted along and removed from the shaft. This frame 34 is provided with right-angle extensions 33^a which are notched at their outer ends so as to engage the inner flange 1^b and thereby held nonrotatable, but at the same time removable as a part of said unit construction when the shaft 8 is removed in the manner hereinafter explained. The opposite parallel extensions 33^a are connected by suitable tie-bolts 35. A tensioning plate 36 is provided on each side of the arms 33 to effect and maintain any desired pressure of the ink roller against the type. Each plate has an eccentric slot 36^a engaging with a camming action the reduced ends of the ink roll rod 32. In order to move these plates a knob 37 is provided, with the result that

when such knob and plates are moved up or down an inward or outward movement of the ink roll is occasioned, thus giving any desired pressure or entirely disabling the inking device if desired. These tensioning plates are adapted to be held in the desired adjusted position by means of a slot and bolt connection with the arms 33, such bolts being shown at 38 and the slots at 36^b. As shown in Fig. 4, the hubs of the arms 33 fit upon the shaft 8 and about the hub portion of the type holder 28 which is secured upon such shaft as described.

Referring next to the cutting mechanism, the same consists of a knife disk 39 butressed on either side by two similar feed rollers 40 and adjustable along the shaft therewith. Said knife disk is rotatably engaged with a smaller disk 41, the latter having one or more projections 41^a adapted to enter a hole or holes in the knife disk and also having a projection 41^b adapted to fit into a key-way 8^a on the shaft, Fig. 4. These feed rollers and knife are secured in their adjusted position by means of the set screws 42. Upon the shaft there is also secured a platen 43, which is held in adjusted position by means of the set screw 44. This platen co-operates with the printing mechanism (if used) on the shaft 9, similar to the printing mechanism already described, but not necessarily having the same markings. In addition the shaft 8 is provided with another feed roller 45 toward the outer end thereof, secured for longitudinal adjustment by means of the set screw 46.

The other shaft 9 is provided with a similar set of printing mechanism, cutting mechanism, feed rollers, and a platen, and as the construction of these parts is exactly the same, the same reference letters are employed. It will be seen that the platen on the lower shaft 9 co-operates with the printing mechanism on the upper shaft 8 and also with the feed roller 45 thereof, and that the platen on the upper shaft co-operates with the printing mechanism on the lower shaft, as well as with the feed roller 45 thereof. Furthermore the knife disks 39 and the middle feed rollers 40 co-operate with each other.

The shaft 8 has fixed bearings in the main frame or yoke, but the shaft 9 is mounted in spring-pressed bearings, with the result that the feed rollers thereof are held yielding against the feed rollers upon the upper shaft. The ends of the shaft 9 are capable of vertical movement in the slots or openings 47 of the main frame, and such shaft is spring-pressed with the result stated by means of plungers 48 contained within bores 49 of the main frame at either end of the shaft. These plungers are held pressed against the shaft by springs 50 whose tension is adjustable by means of the screws

51. Both shafts 8 and 9 are held in place longitudinally by means of the movable collars 52 at the outer ends thereof.

Referring to the feed table and chute and 5 describing the particular embodiment herein shown, I form from one or more pieces of sheet metal, first a paper or check shelf or support; second, a feed-chute; third, a delivery receptacle. The paper shelf or support 10 indicated at 53 is provided at its inner side with a vertical flange 53^a and with a back wall 53^b which is here shown as continuous with the inclined feed-chute 54 also having a vertical flange 54^a formed as a continuation 15 of the flange 53^a. This chute is secured to a flange 1^c of the yoke 1 by means of the screws 55. The delivery box or receptacle 56 is provided with a front wall 56^a which extends upwardly as a part of the feed- 20 chute, the same being an integral part or otherwise, as may be desired or found convenient in manufacture. The feed-chute is provided at a point registering with the mountings upon the two shafts 8 and 9 with 25 a transverse opening 57, Figs. 5 and 6 and the inner edges of said opening are flanged downwardly in order to prevent any obstruction to the paper passing along the feed-chute. At its outer side the feed-chute as 30 well as the shelf or support and the delivery receptacle are supported by means of an irregular-shaped plate or strut 58, one arm of which supports the paper shelf 53, another arm of which extends downward and en- 35 gages under receptacle 56. This plate or strut is secured to the end of the lower limb of the yoke in suitable manner, as by means of the screws 59.

In order to accommodate papers of a 40 greater width or length than the width of the yoke, I provide the paper rest, feed-chute, and delivery receptacle with adjustable bottoms and end flanges. As shown, the paper shelf 53 is provided with a movable 45 and extensible bottom 60 having a vertical flange 60^a sliding along the back wall 53^b. It will be understood that the extensible bottom 60 overlies and is slidably mounted upon the bottom of the shelf 53, the same be- 50 ing held thereon with a friction supplied by means of guide-clips (Fig. 5), each of which comprises a block 61 secured to the under side of the movable plate or bottom 60, a bolt 62 forming a part of the block, 55 a hollow collar 63 through which the bolt passes, a spring 64 within the collar, and a spring clip 65 through which the bolt also passes and against which the spring bears so as to force the spring clip against the un- 60 der side of the bottom of the paper shelf 53. This last mentioned bottom is transversely slotted ~~so~~ as to permit of transverse move- 65 ment of the block 61. In this manner the two bottoms are held against movement or

displacement, except as against positive force 66 applied when it is desired to move the extensible bottom outwardly to accommodate the paper passing through the attachment.

In like manner the feed-chute is provided with a movable extension 66 and the delivery 70 receptacle with an extensible bottom 67, both of which extensions are provided with friction means similar to those just described, and therefore having similar reference characters.

In order to prevent any uneven feeding of the paper that might be caused by the overlapping peripheries of the cutting disks and a resulting uneven cutting of the stub or coupon, I provide a presser means acting 80 on the paper or at near its ends in advance of the action of the cutting mechanism. As hereinafter shown, these means consist of a pair of presser devices, Figs. 4, 9, and 10, mounted near the ends of the upper shaft 8 85 and adapted to bear upon the paper passing through the attachment. These presser devices are similar in construction so that a description of one will apply to both. Each device comprises a presser finger 68 pivoted 90 at 69 to the lower end of an arm 70 whose hub portion is secured to the shaft 8 by means of the set screw 71. The finger is held spring-pressed by the spring 72 against the lower platen in one case and against the 95 lower feed roller 45 in the other case. The finger moreover has its forward end upwardly curved and the same is so positioned that it will act upon the incoming paper and press the same against the platen or 100 roller before the paper is acted upon by the cutting mechanism, with the result that the paper will be held in straight line position in the attachment while being acted upon by the cutting and the printing mechanism. 105

Describing a complete cycle of operation of my machine it will be assumed that the adding machine and the attachment are in normal position indicated in the drawings. A pile or stack of checks, bills or other 110 papers to be acted upon by the machine is placed within the receiving receptacle or shelf 53 and the amount shown on the uppermost check or the like is set up on the keyboard of the adding machine. This uppermost check is then placed in the feed chute, down which it falls until it enters the bite of the presser device and feed rollers. The adding machine is then operated and upon the forward pull of the handle the 115 sector 11 is moved in a clockwise direction, Fig. 2, with the result that the loose pinion 16 will be idly rotated. When the handle is released and thereby permitted to return to its normal position, the return movement of the parts assisted by the spring 14 will move the sector 11 in an anti-clockwise direction to its normal position, during which

- movement it will rotate the pinion 16 one rotation in the opposite direction. At this time, however, the tooth 19^a of the ratchet wheel 19 will engage the pawl 20 and positively move the gear 18. Inasmuch as this gear is secured to the shaft 8, the latter will be given a single rotation and at the same time the other shaft 9 will be correspondingly rotated by reason of the meshing of the gears 18 and 21. Consequently the check or other paper will be printed upon by the printing mechanisms, one printing upon the upper surface of the bill and the other on the under surface. At the same time the bill or statement will be severed by the cutters 39, thereby cutting off a stub or coupon. It will be understood that only a single printing mechanism may be employed at a time for printing upon one side of the paper, and also that the printing mechanism may be adapted to print any desired characters or markings upon the paper. In case the paper is of greater length than the width of the feed chute and the two receptacles when their extensions are in their innermost positions, such extensions may be drawn out laterally as shown in dotted lines in Fig. 4, the extent being determined by the length of the paper.
- It will also be understood that the printing and cutting mechanisms may be used conjointly as shown or independently as desired.
- The foregoing described construction is such that the attachment may be readily applied to or removed from the adding machine, and also may be readily adjusted as respects the printing and cutting mechanisms. Moreover, the different working parts of the attachment may be disassembled with facility, its parts being readily removable from and interchangeable on the two shafts 8 and 9, thereby adapting the attachment to many different forms of work requiring different arrangements in the matter of coupon cutting or not, and the printing on the front or reverse side of either or both, as the case may be. When it is desired to remove any of the mountings from the shafts the entire structure is lifted from the adding machine, whereupon the shafts may be withdrawn upon the removal of the collars 52 and without the removal of any gearing affixed thereto. By reason of the described formation of the frame plate 2, the attachment may be readily locked in proper place with the proper meshing of the gears 16 and 18 by means of the adjusting screw 7 and the slot connection of the upper arms of the frame plate with the studs 5 on the side of the adding machine.

I claim:

1. An attachment for an adding machine or the like comprising, in combination with

an oscillatory driving member of said machine, a concentric auxiliary driving member rotatively engageable with and disengageable from such driving member through axial movement, a rotary printing couple, and operating connections between the same and said auxiliary driving member.

2. An attachment for an adding machine or the like comprising, in combination with an oscillatory driving member of said machine, a concentric auxiliary driving member rotatively engageable with and disengageable from such driving member through axial movement, means for securing said auxiliary member in clutched relation to the driving member of the machine, a rotary printing couple, and operating connections between the same and said auxiliary driving member.

3. An attachment for adding machines or the like comprising, in combination with an oscillatory driving member thereof, an auxiliary driving member axially aligned with the same, clutch elements rotatively connecting said members, a clamping screw securing said elements in clutched relation, a rotary printing couple, and operating connections between the same and said auxiliary driving member.

4. An attachment for adding machines or the like comprising, in combination with a shaft thereof and an oscillating arm on said shaft, a gear segment having a hub telescoped with said shaft and clutched to said arm, a rotary printing couple, and driving connections between the same and said gear segment.

5. An attachment for adding machines or the like comprising, in combination with the frame or casing of such machine, a support adapted to be slid into engagement with the frame at a plurality of points so as to be vertically and horizontally sustained, with provisions for clamping said support in place, limbs rigid with and projecting laterally from said support, a printing couple the members of which are journaled in said limbs, and suitable driving connections for said printing couple.

6. An attachment for adding machines or the like comprising, in combination with the frame or casing of such machine a support adapted to be slid into engagement with the frame at a plurality of points so as to be vertically and horizontally sustained, said support having slotted arms and the frame having screw studs to occupy the slots, limbs rigid with and projecting laterally from said support, a printing couple the members of which are journaled in said limbs, and suitable driving connections for said printing couple.

7. In combination with a support, a main frame, printing mechanism mounted there-

- in; a frame plate to which said frame is secured and which is connected with said support, said support having a pair of supporting studs and a supporting lug, and the 5 frame plate having inclined slots receiving the studs and an inclined portion adjustably connected with said lug, and operating connections for the printing mechanism.
8. In combination with a support, a main 10 frame, printing mechanism mounted therein, a frame plate to which said frame is secured, and which is connected with said support, said support having a pair of supporting studs and a supporting lug, and the 15 frame plate having inclined slots receiving the studs and an inclined portion adjustably connected with said lug, the inclination of said portion being at right angles to the inclination of the slots, and operating connections for the printing mechanism.
9. An attachment for adding machines or the like comprising, in combination with the frame or casing of such machine, a support engageable therewith and rigidly sus- 20 tained thereon at one side thereof; horizontally projecting yoke limbs rigid upon said support and each of U-shape and having shaft bearings in its end-arms, shafts journaled in said pairs of bearings, respec- 25 tively, printing elements mounted upon the shafts, and suitable driving connections for the latter.
10. An attachment for adding machines or the like comprising, in combination with the frame or casing of such machine, a support and gear housing engageable with the same and adapted to be rigidly sustained thereon, horizontal limbs rigid with said support, a printing couple whose members 30 are journaled in said limbs respectively, and gearing housed in said support and arranged to drive said couple.
11. An attachment for adding machines or the like comprising, in combination with the frame or casing of such machine, a support in the form of a flanged plate or hollow casting engageable with the same and adapted to be rigidly sustained thereon, horizontal limbs rigid with said support, a printing 35 couple whose members are journaled in said limbs respectively, and gearing housed in said support and arranged to drive said couple.
12. An adding machine attachment in- 40 cluding a frame, two parallel shafts mounted to rotate therein, printing mechanisms mounted on said shafts respectively, coöperating cutting disks also mounted on said shafts respectively, pairs of feed rollers mounted on said shafts respectively, and clamping the disks between them, and means for operating the shafts.
13. An adding machine attachment in- 45 cluding a shaft having a driving connection with the adding machine, a frame in which the shaft is mounted, and which has a guide flange, a rotary type carrier mounted upon the shaft, parallel plates arranged on opposite sides of such mechanism and having right angled arms, one pair of which coöperate with the guide flange, an ink roller mounted in the other arms, and means for operating the shaft.
14. An adding machine attachment in- 50 cluding a shaft, a frame in which the shaft is mounted and which has a guide flange, a rotary type carrier mounted upon the shaft, parallel plates arranged on opposite sides of such mechanism and having right angle arms, one pair of which coöperate with the 55 guide flange, an ink roller mounted in the other arms, means for adjusting said roller toward and away from the type carrier, and means for operating the shaft.
15. A printing attachment including 60 printing mechanism, and a feed chute, comprising a fixed plate, a laterally movable plate slidable thereon, and friction device for holding said plates in engagement.
16. A printing attachment including 65 printing mechanism and a paper receiver, feed chute, and delivery receptacle, said receiver, chute and receptacle having laterally extensible portions to accommodate different widths or lengths of paper.
17. A printing attachment for an adding 70 machine including printing mechanism, a yoke in which such mechanism is mounted and which is adapted to be connected with an adding machine, means for operating the printing mechanism, and a paper feed chute having a laterally extensible portion movable through the opening of the yoke.
18. An attachment for adding machines or the like comprising a suitable supporting 75 frame, a rotary printing couple journaled therein, one-way driving mechanism therefor, including an oscillating gear segment, a stop for preventing overturning of the members of the printing couple, said stop normally locking the same, and a projection on the gear segment to act upon said stop.
19. In combination, rotary printing mechanism and driving connections therefor in- 80 cluding a segmental gear, a pinon driven by the gear, a ratchet on the pinon, a shaft on which the printing mechanism is mounted, a wheel on the latter shaft, a pawl located on the wheel, and coöperating with the ratchet, a stud on the segmental gear, a 85 stud on said wheel, and a pivoted arm arranged in the path of the gear stud and having a slot adapted to engage the wheel stud when in its home position to prevent overthrow of the shaft.
20. An attachment for adding machines or the like, comprising, in combination with an oscillating driving element thereof, an 90

auxiliary oscillating member driven thereby and spring returned, a rotary printing couple, and one-way driving connections between the latter and the printing couple, 5 which provide for operating the latter only upon the return stroke of the oscillating member.

21. An attachment for adding machines or the like, comprising, in combination with 10 an oscillating driving element thereof, an auxiliary oscillating member driven thereby,

a normally locked rotary printing couple, and one-way driving connections between the auxiliary member and the printing couple, which provide for operating the latter 15 only upon the return stroke of the oscillating member, with provisions for unlocking the printing couple ahead of such stroke.

FRANK C. RINSCHE.
